ATTORNEY

UNITED STATES PATENT OFFICE.

CHARLES FRED PRESSLER, OF FORT WAYNE, INDIANA.

DISPENSING-PUMP.

No. 913,848.

Specification of Letters Patent.

Patented March 2, 1909.

Application filed November 11, 1908. Serial No. 462,036.

To all whom it may concern:

Be it known that I, CHARLES F. PRESSLER, a citizen of the United States of America, and resident of Fort Wayne, in the county 5 of Allen and State of Indiana, have invented certain new and useful Improvements in Dispensing-Pumps, of which the following is a specification.

This invention relates to improvements in 10 dispensing pumps of the class designed to discharge measured quantities of fluid, and the object of the improvement is to afford a self-measuring dispensing pump of the reciprocating type that will discharge an equal 15 amount of fluid at each cycle of its movement.

It is generally understood that in pumps having a reciprocating plunger or piston, the discharge from the end of the cylinder, 20 through which the piston-rod extends, is less in quantity than from the opposite end because of the displacement of fluid by the piston-rod.

The present invention will therefore 25 compensate for the displacement effected by the piston-rod of liquid in the corresponding end of the cylinder of the pump.

The object of this invention is accomplished by the construction illustrated in the 30 accompanying drawings, in which—

Figure 1. is a side elevation of the pump showing the cylinder partly in section. Fig. 2. is an elevation of the same in a plane at 35 right angles to that of Fig. 1, and Fig. 3. is a detail view showing an adjustable crank for driving the compensating plunger.

Similar numerals of reference indicate corresponding parts throughout the several 40 views, and referring now to the same: 1 is the pump cylinder, and 2 is a piston operating therein, the piston having a piston-rod 3 that has a connecting-rod 4 for driving the same. The connecting-rod has connection 45 with a revoluble wheel 5 by which it is actuated. A shaft 6 affords support for the wheel 5 and is mounted in a bracket 7 that extends above the cylinder. A crank 8 is fixed upon the end of the shaft and is disposed 50 oppositely respecting the pin 9 on the wheel to which the connecting-rod is attached. In the crank 8 is a sliding block 10 from which extends a pin 11, and an adjusting screw 12 in the crank extends through 55 the block to effect adjustment thereof.

From the top of the cylinder 1 extends a

secondary cylinder 13 in which a plunger 14 is arranged to reciprocate by the movement of the crank 8, there being a connecting-rod 15 between the plunger and the pin 11 on the 60 crank for the purpose. It will be observed that the pin 11 and pin 9 are oppositely disposed relative to the axis of the shaft 6, and therefore it follows that the movement of the piston and plunger will be correspondingly 65 in opposite directions. By adjusting the block 10 the movement of the plunger 14 can be made such as to draw within the secondary cylinder during the downward stroke of the piston, sufficient fluid as will compensate 70 during the return of the piston for the liquid displaced by the presence of the piston-rod in the upper part of the cylinder.

At the connection of the piston-rod 3 and connecting-rod 4 is a cross-head 16 that 75 works in ways 17 to prevent strain and lost motion. This cross-head has an extension 18 which is adapted to become engaged by one or the other of the stops 19 or 20 according to the adjustment of the latter and thereby regulate the length of stroke of the piston and consequent discharge of fluid from the pump. The stops are adjustably fixed upon an adjustable shaft 21 operated by a handle 22 so that either one or the other of the stops 80 may be brought over in line with the path of the extension 18 as desired. Each stop has an adjusting-screw 23 by means of which delicate variations of adjustment may be made. 90

The cylinder has a suction pipe 24 with inlet valves 25 and 26 connecting the corresponding ends of the cylinder, and also a discharge pipe 27 with outlet valves 28 and 29 connecting the corresponding ends of the 95 cylinder and through which the fluid is discharged after having been drawn through the suction pipe.

Motion may be imparted to the wheel 5 by any suitable means, such as by a gear 30 100 driven by a crank 31.

Having described my invention, what I claim as new and desire to secure by Letters Patent is:—

1. In a dispensing pump having a cylinder 105 with a piston operating therein and a piston-rod extending from the piston through one head of the cylinder, a secondary cylinder having communication with the other cylinder at the end thereof in which the piston-rod extends, a plunger operating in the secondary cylinder, and means to actuate the 110

piston and plunger oppositely respecting one another.

2. In a dispensing pump, a cylinder, a piston operating therein, a piston-rod extending 5 through the upper head of the cylinder and connected with the piston to actuate the same, a secondary cylinder communicating with the other cylinder at the upper end thereof, a plunger operating in the secondary cylinder, suitable mechanism in connection 10 with both the piston-rod and plunger adapted to actuate the same oppositely respecting one another, and adjustable means adapted to regulate the movement of the plunger relative to that of the piston.

15 3. In apparatus of the class described, a

reciprocating pump having a piston-rod for operating the same, a secondary cylinder in communication with that end of the pump-cylinder through which the piston-rod extends, a plunger operating in the secondary cylinder, means in connection with the piston-rod and plunger adapted to actuate the same oppositely, and adjustable stops adapted to limit the movement of said 25 piston-rod and plunger.

In testimony whereof I affix my signature, in presence of two witnesses.

CHARLES FRED PRESSLER.
